UNITED STATES PATENT OFFICE.

FRANK S. BARKS, OF ST. LOUIS, MISSOURI.

VALVE MECHANISM.

Application filed April 6, 1925. Serial No. 20,941.

My invention relates to a valve mechanism and particularly to a quick acting valve mechanism similar to that shown in connection with the lubricating system set forth in my Patent 1,601,490, dated September 28, 1926.

In the accompanying drawings, which illustrate one form of valve made in accordance with my invention, together with 10 a slight modification thereof, Figure 1 is a vertical central section through the valve and a cylinder controlled thereby; Figure 2 is an enlarged horizontal section through the valve; Figure 3 is a section taken on 15 the line 3—3 of Figure 2; Figure 4 is an end view of the valve; Figure 5 is a section taken on the line 5—5 of Figure 2; Figure 6 is a top plan view, partly in section, showing a modified form of both valve and cylinder; Figure 7 is a vertical central section 20 through the parts shown in Figure 6; Figure 8 is an enlarged section on the line 8—8 of Figure 7; and Figure 9 is an enlarged section on the line 9—9 of Figure 7.

25 Referring first to Figures 1 to 5 inclusive, 10 indicates a cylinder similar to that shown and described in my prior patent, above referred to, and containing a piston 11 having a stem 12 of relatively large diameter so that the cross sectional area of the front chamber 13 is much less than the area of the rear face of the piston. The chamber 13 is adapted to contain grease or other lubricant, the flow of which to and from 30 said chamber is controlled by the valve mechanism hereinafter to be described and which forms the subject-matter of the present invention. Compressed air or other actuating fluid is supplied to the rear face of 35 the piston being also controlled by said valve mechanism. The stem 12 is provided with an extension 14 carrying an arm 15 for imparting motion to the valve stem.

40 Secured to the cylinder 10 is a valve casting 16 provided with a longitudinal base in which is a valve stem 17. Formed, preferably in integral upward extensions of the valve casing, are air and grease chambers 18 and 19 respectively. Ports 20 and 21 45 extend from the air chamber 18 to the valve base and, through these, the chamber is alternately placed in communication with a supply port 22, and an exhaust port 23 by means of an annular recess 24 in the valve

stem. Ports 25 and 26 extend between the 55 grease chamber 19 and the base of the valve casing and thus enable the chamber to be put alternately into communication with discharge port 27 and supply port 28 through an annular groove 29 in the valve stem. 60 Formed in the valve casing, between the chambers 18 and 19, is a relief port 30 extending completely around the valve stem to prevent any air which might leak around the valve stem from reaching the grease 65 ports.

The valve stem is provided with an extension formed by a rod 31 passing freely through an opening in the arm 15 and guided at the forward end is a bracket 32, supported in any suitable manner, as for example by side rods, as shown in my above mentioned patent. This bracket also forms a guide for the extension 14 of the piston stem. Surrounding the rod 31, forward of 70 the arm 15, is a coil spring 33 carried by an adjustable collar 34, and a similar coil spring 35 carried by an adjustable collar 36 surrounds the rod at the rear of the arm. Movement of the arm is imparted to the 75 valve stem by contact of the arm with one or the other of the springs 33 or 35. In order that the valve may be quick acting the stem is held against movement until the spring (33 or 35) is sufficiently compressed 80 to throw the stem from one extreme of its movement to the other. This restraint of movement of the stem is accomplished by two yielding members, preferably balls 85 37 (Figure 2) arranged at opposite sides of the stem in cylindrical extension 38 of the valve casing and engaging with one or the other of two annular grooves 39 and 40 formed in the stem and having inclined walls. Coil springs 41 in the extension 38 normally force 90 the balls into one of the grooves and thus offer resistance to the longitudinal movement of the stem. The tension of the springs may be varied by means of threaded rods 42 extending between plugs 43 bearing 95 on the outer ends of the springs. By this construction the pressure of the two balls is at all times equal so that no lateral strain is imparted to the stem. A nut 44 at the rear end of the stem, and a washer 45 at the front end serve as positive stops to prevent the valve from over-movement. Connecting the air chamber 18 with the rear

end of the cylinder is a pipe 46, and a pipe 47 connects the grease chamber 19 with the front cylinder chamber 13. The various connections leading to and from the ports 22, 23, 27 and 28 have not been shown as they form no part of the present invention and would require the illustration of the entire lubricating system of my above mentioned application.

- 10 The operation of my valve is, briefly, as follows:

Assuming the parts to be in the position shown in Figure 1, the compressed air, or other motive fluid, will enter the valve casing through supply port 22 and thence pass by way of groove 24, port 20, and pipe 46 to the rear end of the cylinder, thus forcing the piston forward to expel the grease from chamber 13 through pipe 47 into grease chamber 19 and thence through port 25 and groove 29 to discharge port 27. As the piston travels forward the arm 15 will, when nearing the end of the stroke, engage the spring 33 and compress it until its tension 25 is sufficient to overcome the restraining effect of the balls 37 on the stem. The relative tension of the spring 33 (and 35) to that of springs 41 should be so adjusted that the spring 33 will be sufficiently compressed 30 to complete the movement of the stem before the retarding effect of the balls is overcome. As soon as this occurs the stem will be at once thrown into the position shown in Figure 2, thus placing the rear end of 35 the cylinder in communication with the exhaust port 23 through pipe 46, port 21, and groove 24. At the same time the cylinder chamber 13 will be placed in communication with the supply port 28 through pipe 47, 40 port 26, and groove 29, thus reversing the direction of travel of the piston. On the return stroke the arm 15 engages and compresses the spring 35 until the retarding effect of the balls is overcome and the valve 45 stem returned to the position shown in Figure 1 to start anew the cycle of operation above set forth.

In Figures 6 to 9 inclusive, I have shown a modification of my valve to adapt it for 50 use in connection with a cylinder in which a common supply of motive fluid is used on both sides of the piston. In this construction the cylinder 10' differs but slightly from the cylinder 10, but its piston 11 is 55 not provided with an enlarged stem but is attached to a piston 14' carrying an arm 15' cooperating with the springs 33 and 35 on the valve stem 17. A rod 50 is used to guide the arm 15'. The valve casing 16' differs 60 somewhat in form from the casing 16 having in place of the air and grease chambers 18 and 19, two air chambers 18' and 19' reversed in position from the corresponding chambers in the casing 16, and a feed chamber 51 supplied by pipe 52 communicates

with the base of the casing through ports 22' and 28'. The exhaust ports 23' and 27' are formed in the bottom of the casing.

The operation of this form of the device is, briefly, as follows:

The parts being in the position shown in Figure 7, motive fluid enters the feed chamber 51 through pipe 52 and thence passes through port 28', groove 24, chamber 19', and pipe 47' to the cylinder chamber 13 75 thus forcing the piston in the direction indicated by the arrow. At the same time the fluid from the rear end of the cylinder passing out through the pipe 46', chamber 18', port 21', and groove 29 to the exhaust port 23'. The arm 15' compresses the spring 35 in the manner hereinbefore described and moves the stem 17 to the opposite end of its stroke in which position the cylinder chamber 13' is placed in communication 80 with the exhaust port 27' through the pipe 47', chamber 19', port 25', and groove 24. At the same time motive fluid is admitted to the rear end of the cylinder from the fluid chamber 51 through port 22', groove 29, port 20', and pipe 46'. In this form of the device the quick acting function of the valve is secured in substantially the same manner as in the form first described, the only difference being in the fluid connections 85 and the necessary changes in form of the parts to adapt them to such changed connections.

In view of the above, it will be seen that the several objects of the invention are 100 achieved and other advantageous results attained.

As many changes could be made in carrying out the above constructions without departing from the scope of the invention, 105 it is intended that all matter contained in the above description or shown in the accompanying drawings shall be interpreted as illustrative and not in a limiting sense.

Having fully described my invention, 110 what I claim as new and desire to secure by Letters Patent of the United States is:

1. In a device of the class described, the combination with a valve casing provided with ports, of a valve for controlling said ports, and provided with a stem, a spring carried by said stem, means engaging said spring to move the stem, and restraining means for the valve comprising a pair of oppositely disposed spring pressed balls free to rotate and engaging with a recess in the valve.

2. In a device of the class described, the combination with a valve casing provided with ports, of a valve for controlling said ports and provided with a pair of grooves, spring actuating means for said valve, restraining means for said valve comprising a pair of opposed balls engaging said grooves, springs bearing on said balls, plugs engag- 130

ing said springs, and adjustable means connecting said plugs for varying and equalizing the pressure on said balls.

3. In a device of the class described, the combination with a valve casing having a bore extending through it and provided with outlet and inlet ports communicating with said bore, a stem in said bore for controlling said ports, spring actuated means for actu-

ating said stem, yielding means for holding said stem against said actuating means, and stops carried by said stem external to said casing and adapted to strike against the ends of the casing to positively limit the movement of the stem.

In testimony whereof, I have hereunto set my hand this the 3rd day of April, 1925.

FRANK S. BARKS.
